ANDREW S. GREENE, OF INDIANAPOLIS, INDIANA.

BOILER STAY-BOLT.

1,161,659.

Specification of Letters Patent. Patented Nov. 23, 1915.

Application filed May 8, 1915. Serial No. 25,599.

To all whom it may concern:

Be it known that I, ANDREW S. GREENE, a citizen of the United States, residing at Indianapolis, in the county of Marion and State of Indiana, have invented a new and useful Boiler Stay-Bolt, of which the following is a specification, reference being had to the accompanying drawings, and to the letters and figures of reference marked thereon.

This invention relates to steam boilers including the fire-boxes thereof, the invention having reference more particularly to stay-bolts that are designed to be connected to oppositely arranged sheets of the boiler structure, especially the type of bolt that is commonly known as a "tell-tale" bolt.

An object of the invention is to provide an improved boiler-stay appliance of such construction as to include a stay-bolt and connections therefor which will permit detection of fracture of the stay-bolt without requiring removal or disturbance of the connection, to the end that time and labor may be saved in the inspection of the stay-bolts.

Another object is to provide a non-leaking stay-bolt which shall be simple and inexpensive and permit ready removal of the stay-bolt when fractured, and which shall be so constructed that in case of fracture of the stay-bolt its head cannot be blown off.

A still further object is to provide an improved stay-bolt of the above-mentioned character that with its connections shall be so constructed as to be adapted to be non-obstructive on the exterior of the boiler.

With the above-mentioned and other objects in view, the invention consists in a stay-bolt of novel construction and a novel guard for the head of the stay-bolt, all permitting instant detection in case of breakage of the stay-bolt when in service, more especially when the boiler is under steam pressure; and the invention consists also further in the parts, and combinations and arrangements of parts, as hereinafter particularly described and further defined in the accompanying claims.

Referring to the drawings, Figure 1 is a side view of the improved stay bolt and its connections including its guard; Fig. 2 is a plan view of the head of the improved stay-bolt; Fig. 3 is a section of the improved stay-bolt and its connections as applied to two boiler plates or sheets, the plane of the

section corresponding to the line A A on Fig. 1; Fig. 4 is an internal or rear plan of the improved guard; Fig. 5 is a front view of the preferred form of sleeve in which the head of the stay-bolt when in use is seated; Fig. 6 is a plan of a packing washer employed between the stay-bolt head and its guard; Fig. 7 is a plan or outer end view of the "flush" type or modified form of the improved stay-bolt and connections; Fig. 8 is a sectional elevation of the modified form of construction applied to a boiler sheet; and, Fig. 9 is a fragmentary side view of the stay-bolt proper.

Similar reference characters on the different figures of the drawings indicate like parts or features of construction herein referred to in detail.

As illustrating the purpose of the invention and mode of application, fragments of two fire-box plates or sheets are illustrated, the numeral 1 indicating the inner sheet and 2 the outer sheet. The improved stay-bolt comprises a cylindrical main or body portion 3 having external screw threads 4 near one end thereof that are screwed into the inner sheet 1 by means of a squared end portion 5 left on the bolt when manufactured but which is cut off after the bolt is screwed into the sheet, the remaining end of the bolt being subsequently upset to form a head 6 on the inner side of the sheet. The opposite end of the main portion of the bolt has a head 7 thereon which preferably is spherical in contour, but in some cases may have a substantially hemispherical end portion 8 and an approximately conical front portion 9. The front of the head has a cylindrical projection 10 thereon in which is a bore 11 that extends through the head and into the body portion of the stay-bolt as far as may be desired, preferably nearly to the opposite end of the stay-bolt.

A suitable sleeve or bushing 12 is provided which has a suitable opening or bore 13 extending therethrough, and an annular ball socket 14 is formed in the outer portion of the sleeve so as to extend about the opening or bore and form a seat for the under or back portion of the head of the bolt, the sleeve having external screw threads 15 that are screwed into the outer sheet 2.

A suitable guard for the head 7 is provided, and in the preferred form comprises an annular body portion 16 having a hex-

agonal exterior 17 to which a wrench may be applied, and a dome-shaped portion 18 on the front of the body portion of suitable contour to cover but not have contact 5 with the front of the head, the middle or crown of the dome-shaped portion having an aperture 19 to freely receive the nipple-like projection 10 of the bolt head. The body portion 16 has internal screw threads 10 20 to engage the screw threads 15 of the sleeve, and has also a shoulder 21 which in use is seated on the outer end of the sleeve. An annular packing or gasket 22 is provided which is fitted closely over the projection 10 and is compressed between the 15 front of the head 7 and the inner side of the portion 18 of the guard so as to prevent the escape of water or steam through the aperture 19 at the side of the projection 10 in 20 case of leakage between the head and the sleeve.

When the "flush" type of stay-bolt, which is set so that its head does not project out beyond the sheet, is required or desired, the 25 sleeve or bushing is slightly modified and has a strong body portion 23 having the opening or bore 13 therein, the front of the body portion having an annular wall 24 thereon which has external screw threads 25 30 to be screwed into the front sheet 2. The annular wall forms a recess having a bottom 26 on the body portion 23, and the wall has internal screw threads 27. The guard also is slightly modified and comprises a 35 main portion 28 adapted to be inserted into the recess to the bottom thereof and not extend outward to the front end or top of the wall 24, the main portion having external screw threads 29 thereon to engage the internal screw threads 27. The body portion 40 has a dome-shaped inner side 30 that receives but does not have contact with the front of the head of the bolt, the under side of the head being seated in the ball socket 45 45 14 which is formed in the body portion 23 so as to extend downward from the bottom 26 of the recess. The guard has a squared projection 31 fixed on its front or top to receive a wrench. The guard has also an aperture 32 therein that extends through the main portion 28 and the extension thereof that loosely receives the nipple-like projection 19 of the bolt head. The packing 22 is placed on the front of the bolt head and 50 55 extends about the projection 10 in contact with the inner side 30 of the guard so as to prevent leakage through the aperture 32. The proportions may be such that the end of the projection 10 and the extension 31 60 65 shall be substantially on the plane of the front of the wall 24 of the sleeve and correspond to the outer face of the outer boiler sheet.

In practical use the stay-bolt resists the 65 outward pressure between the sheets or boiler

plates, as will be understood, and in case the bolt becomes fractured between the sheets or plates leakage will occur into the bore 11 and pass out through the head and the nipple 10 to the atmosphere, and therefore 70 the damage may be readily detected without necessitating the removal of the guard. In case the steam pressure exerting its force through the fracture, which in some cases may be complete, tends to force the head 75 from the body portion of the bolt, the head is retained by the guard, although in such case some leakage of water or steam may occur past the head and the seat 14 but will be stopped by the packing 22 and prevented 80 from escaping into the atmosphere, or if escaping will indicate the source of the defect. In case it is necessary to replace a broken stay-bolt the guard is removed from the sleeve, after which the broken bolt may 85 be removed as usual to be followed by the insertion of a new stay-bolt, after which the guard and a new packing 22 is applied as before.

Having thus described the invention, what 90 is claimed as new is,—

1. A stay-bolt having a head provided on its top with a projection extending from the head on the axis of the body portion of the stay-bolt, the stay-bolt having a bore 95 therein extending inward from the end of the projection, and a guard for the head to cover the top thereof and having a central aperture to loosely receive the projection.

2. A stay-bolt appliance including a 100 sleeve, a stay-bolt having a head provided on its front with a projection and having also a bore therein extending inward from the end of the projection, and a guard for retaining the head adjacent to the sleeve 105 with the body portion of the stay-bolt extending through the sleeve, the guard having an aperture therein to loosely receive the projection of the head.

3. A stay-bolt appliance comprising a bolt 110 main portion having a head provided on its front with a projection, the appliance having a bore therein that is continuous from the end of the projection to and through the head and into the main portion, a sleeve 115 on the appliance in which to seat the head, a guard connected to the sleeve for covering and retaining the head adjacent to the sleeve and having an aperture therein to receive the projection of the head, and a packing 120 extending about the projection between the head and the guard and enabling the head and the projection thereof to close the aperture in the guard about the exterior of the projection.

4. In a stay-bolt structure, the combination of a sleeve, a bolt head seated in the sleeve and having a projection on its front, the head and the projection having a continuous bore that extends therethrough, a 125

- packing ring on the front of the head extending about the projection, and a guard connected to the sleeve and having a front portion in contact with the packing ring,
5 said front portion being clear of the front of the head and having an aperture therein through which said projection extends to form a conducting passage from the head and through and beyond the guard.
10 5. In a boiler stay-bolt structure, the combination with two oppositely arranged boiler plates, of a bushing secured in one of the plates, a guard secured to the bushing and having a central aperture therein, a
15 gasket on the inner side of the guard extending about and close to the orifice of said aperture, and a bolt in the bushing and secured to the opposite one of the boiler plates, the bolt having a head that is seated in the
20 bushing clear of said guard and provided

with a projection on its front that extends through and in contact with said gasket and through said aperture, the bolt having a bore that extends inward from the end of said projection and through the head and 25 into the body portion of the bolt.

6. In a stay-bolt, a head having an integral projection extending from the front of the head, with a bolt body integrally formed on the back of the head and a bore 30 extending from the end of the projection and through the projection and the head and into the bolt body.

In testimony whereof, I affix my signature in presence of two witnesses.

ANDREW S. GREENE.
